FLOOR LAMP OR SIMILAR ARTICLE

Roland T. Hughes, Oak Park, Ill.

Application October 18, 1949, Serial No. 5,553

Term of patent 7 years

(Cl. D48—20)

To all whom it may concern:

Be it known that I, Roland T. Hughes, a citizen of the United States, residing at Oak Park, in the county of Cook and State of Illinois, have invented a new, original, and ornamental Design for a Floor Lamp or Similar Article of which the following is a specification, reference being had to the accompanying drawing, forming part thereof.

In the drawing:

I claim:

The ornamental design for a floor lamp or similar article, substantially as shown.

ROLAND T. HUGHES.
